Carsello

[11] Patent Number: Des. 304,019

[45] Date of Patent: ** Oct. 17, 1989

[54] COMBINED MOTION SENSOR AND MOUNTING FOR ADJUSTABLE FLOOD LIGHTS

D. 269,553 6/1983 Johnson et al. D26/63
4,383,250 5/1983 Galvin ..... 340/566 X
4,549,092 10/1985 Matsuoka et al. ..... 340/540 X

[75] Inventor: John P. Carsello, Telford, Pa.

Primary Examiner—Susan J. Lucas
Attorney, Agent, or Firm—Laney, Dougherty, Hessin & Beavers

[73] Assignee: The Lamson & Sessions Co., Cleveland, Ohio

[57] CLAIM

[**] Term: 14 Years

The ornamental design for a combined motion sensor and mounting for adjustable flood lights, as shown and described.

[21] Appl. No.: 835,325

DESCRIPTION

[22] Filed: Feb. 24, 1986

FIG. 1 is a top plan view of a combined motion sensor and mounting for adjustable flood lights showing my design;

[52] U.S. Cl. D10/106; D26/63; D26/138

FIG. 2 is a front elevational view thereof;

[58] Field of Search D10/104, 106, 121; 340/521, 540-546, 555, 556, 557, 565-578; D26/24, 63, 138, 140

FIG. 3 is a bottom plan view thereof;

FIG. 4 is a rear elevational view thereof;

FIG. 5 is a left side elevational view thereof;

FIG. 6 is a right side elevational view thereof;

FIG. 7 is a bottom, front perspective thereof on an enlarged scale.
